UNITED STATES PATENT OFFICE.

PAUL A. GOURTOFF, OF EDGEWATER, LONG ISLAND, NEW YORK.

AEROPLANE KITE.

Application filed August 23, 1923. Serial No. 659,001.

To all whom it may concern:

Be it known that I, PAUL A. GOURTOFF, a citizen of the United States, residing at Edgemere, L. I., in the county of Queens and State of New York, have invented Improvements in Aeroplane Kites, of which the following is the specification.

The invention relates to improvement in the shape of kites. Heretofore the kites 10 were made of the two distinct forms: (1) ordinary one plane kite and (2) box kite. The object of my improvement is to give them a shape of an aeroplane (monoplane or biplane); also to attach two flaps at the bottom of kite. The purpose of these flaps is to make noise similar to that of an aeroplane.

The invention is illustrated in the accompanying drawing, in which Fig. 1 is the plan; Fig. 2 is the side view, and Fig. 3 is 20 the front view, or section A—A.

The frame work, or body, consists of three sticks 1—1—1 joined together at the ends 2—2; two spreaders 3—3 keep these sticks spread apart: two at the top and one at 25 the bottom.

To the end of the body a tail 4 is attached. It consists of a semicircular frame on which paper is stretched.

Planes (wings) 5—5 are made of a wooden 30 frame, on which paper or cloth is stretched. One wing is attached to the two upper sticks of the body and one to the lower stick. They are detachable. If both planes (wings) attached, it makes the form of a biplane. 35 With one plane attached and the lower stick of the body omitted it makes the form of a monoplane.

Planes (wings) are tied together with the aid of strings 6—6.

40 Flaps 7—7 are made of stiff paper of semi-circular form and attached to the lower plane with a string 8.

All aeroplane-kites can be used to fly as any ordinary kite attached to a long string.

45 I am aware that prior to my invention there were made many different types of kites of plane and box types; but none of them in form of an aeroplane; therefore

I claim:

50 1. An aeroplane kite comprising three sticks fastened together and substantially in contact near their ends, said sticks being bowed out from each other at their intermediate portions, a pair of planes at the bowed out portions, one of which comes transversely across two of said sticks, the

other plane coming transversely across the other of said sticks and bracing means extending from one stick to the other at their bowed out portions.

60 2. An aeroplane kite comprising three sticks fastened together and substantially in contact near their ends, said sticks being bowed out from each other at their intermediate portions, a pair of planes at the bowed out portions, one of which comes transversely across two of said sticks, the other plane coming transversely across the other of said sticks and a plurality of triangular cross-frames between the sticks at 70 the region of the planes.

65 3. An aeroplane kite comprising three sticks fastened together and substantially in contact near their ends, said sticks being bent out from each other at their intermediate 75 portions, a pair of planes at the bent out portions, one of which comes transversely across two of said sticks, the other plane coming transversely across the other of said sticks and strings for tying one plane from the 80 other substantially at their outer portions.

70 4. An aeroplane kite comprising three sticks fastened together and substantially in contact near their ends, said sticks being bent out from each other at their intermediate 85 portions, a pair of planes at the bent out portions, one of which comes transversely across two of said sticks, the other plane coming transversely across the other of said sticks and means for bracing the planes one from 90 the other substantially at their outer portions.

75 5. An aeroplane kite comprising three sticks fastened together and substantially in contact near their ends, said sticks being bent out from each other at their intermediate 95 portions, aerofoil means supported at said bent out portions and a tail supported near one end of two of the sticks, the other stick stopping short of the tail.

100 6. An aeroplane kite comprising a plurality of sticks fastened together and substantially in contact near their ends, said sticks being bent out from each other at their intermediate portions, the rear ends of said sticks being together and substantially in contact for a considerable length, aerofoil means supported at said bent out portions and a tail held in place by being interposed between said sticks at their rear ends.

PAUL A. GOURTOFF.
